The ornamental design for a flanged ring, as shown and described.

DESCRIPTION

FIG. 1 is an upper plan view of a flanged ring embodying a first embodiment of our inventive design;

FIG. 2 is a front elevational view of the flanged ring of FIG. 1, wherein the rear elevational view is identical to FIG. 2; FIG. 3 is an enlarged view of portions of the flanged ring taken at view 3 of FIG. 2, illustrating knurled surfaces at outermost peripheral surfaces of the flanged ring;

FIG. 4 is a right side elevational view of the flanged ring of FIG. 1, wherein the left side elevational view is identical to FIG. 4;

FIG. 5 is a bottom plan view of the flanged ring of FIG. 1; FIG. 6 is an upper left front perspective view of the flanged ring of FIG. 1;

FIG. 7 is an enlarged view of portions of the flanged ring taken at view 7 of FIG. 6, illustrating a knurled surface located on an inner portion of the flanged ring;

FIG. 8 is an enlarged view of portions of the flanged ring taken at view 8 of FIG. 6, illustrating knurled surfaces at outermost peripheral surfaces of the flanged ring;

FIG. 9 is an enlarged view of portions of the flanged ring taken at view 9 of FIG. 6, illustrating a knurled surface at an outer peripheral surface of the flanged ring;

FIG. 10 is an upper plan view of a flanged ring embodying a second embodiment of our inventive design;

FIG. 11 is a front elevational view of the flanged ring of FIG. 10, wherein the rear elevational view is identical to FIG. 11; FIG. 12 is an enlarged view of portions of the flanged ring taken at view 12 of FIG. 11, illustrating knurled surfaces at outermost peripheral surfaces of the flanged ring;

FIG. 13 is a right side elevational view of the flanged ring of FIG. 10, wherein the left side elevational view is identical to FIG. 13;

FIG. 14 is a bottom plan view of the flanged ring of FIG. 10; FIG. 15 is an upper left front perspective view of the flanged ring of FIG. 10;

FIG. 16 is an enlarged view of portions of the flanged ring taken at view 16 of FIG. 15, illustrating a knurled surface located on an inner portion of the flanged ring;

FIG. 17 is an enlarged view of portions of the flanged ring taken at view 17 of FIG. 15, illustrating knurled surfaces at outermost peripheral surfaces of the flanged ring; and,

FIG. 18 is an enlarged view of portions of the flanged ring taken at view 18 of FIG. 15, illustrating a knurled surface at an outer peripheral surface of the flanged ring.
